CIGARETTE HOLDER

Filed Dec. 12, 1927

INVENTOR
James Harmon Abbott
BY
Cyrus N. Anderson
ATTORNEY

UNITED STATES PATENT OFFICE

JAMES HERMAN ABBOTT, OF PHILADELPHIA, PENNSYLVANIA

CIGARETTE HOLDER

Application filed December 12, 1927. Serial No. 239,284.

My invention relates to devices for holding cigarettes as they are being smoked, and it has for its general object to provide means whereby cigarettes may be held at points intermediate their ends, preferably about their middle points, so that both ends may be lighted and smoked simultaneously.

It also is an object of the invention to provide a holder of the character indicated having means whereby upon the insertion of the middle portion of a cigarette into the receiving recess of the holder the wrapper thereof is punctured automatically, whereby the smoke may be drawn from either or both of the burning ends of a cigarette.

To these and other ends the invention comprehends the construction as hereinafter described in detail, particularly pointed out in the claims; and as illustrated in the drawings wherein certain forms of construction embodying the invention and illustrating the principle thereof are depicted.

It will be understood that the invention is susceptible of embodiment in holders of other construction than those shown, and that various changes in the details of construction may be made within the scope of the claims without departing from the invention or the principle thereof.

30 In the drawings:

Fig. 1 is a view in perspective of a holder embodying the invention which is adapted for holding cigarettes for smoking with either end or both ends thereof lighted;

35 Fig. 2 is a view in longitudinal section taken in a plane substantially at right angles to the length of a cigarette which may be held and supported thereby;

Fig. 3 is a transverse sectional view taken 40 along the line 3—3 of Fig. 1;

Fig. 4 is a view in side elevation of the outer or holding end portion of the holder shown in Fig. 1, with the cigarette removed;

45 Fig. 5 is a view in longitudinal section of a modified construction of holder, the said

view being taken along the line 5—5 of Fig. 6;

Fig. 6 is a view in side elevation;

Fig. 7 is a view of a holder provided with means whereby the outer end or cigarette-holding portion thereof may be held in elevated relation with respect to a table or other support upon which the said holder may be placed; and

Fig. 8 is a view in perspective of the means shown in Fig. 7 for supporting the outer end of the cigarette-holding portion of the holder in elevated relation to a table or other support upon which it may be placed.

In the drawings I have shown a holder comprising an elongated tapered stem-like member 1 having a passageway 2 extending longitudinally thereof as usual and in known manner.

In the construction as illustrated in Figs. 1 to 4 inclusive the opening 2 terminates at its forward or outer end in an enlarged portion 3 which is closed by means of an ornamental cap 4 which fits over the outer end of the said holder. The holder is provided in 70 adjoining relation to its outer end with a notch 5 which extends transversely thereof. The said notch is circular in cross section to correspond with the shape in cross section of a cigarette and the said notch opens upon one side of the holder, as indicated at 6. In the insertion of cigarettes into the notch 5 they are placed in the opening 6 and pushed laterally thereonto. Preferably the opening 6 is of a width somewhat less than the diameter of the notch in a direction lengthwise of the holder, but if desired the opening at 6 may be of the same width as the width of the said notch at its widest portion.

In order that the wrappers of cigarettes 85 may be punctured as the middle or other portions thereof are pressed or pushed into the notch 5 through the top opening 6 thereof I have provided a puncturing device 10 mounted in the holder and having an end 90

portion 11 thereof projecting into and transversely of the said notch. Preferably the outer or upper edge of the projecting end portion 11 is shaped to constitute a knife edge. The essential thing, however, is that the projecting end portion shall be of a character to puncture the wrappers of cigarettes as they are pressed down into the notch 5.

10 In order to positively and effectively retain the cigarettes within the notch 5 as they are being smoked I have provided a retaining device consisting of a narrow strip of metal 15 which is mounted in a shallow groove 16 in a side of the holder and inwardly of the notch 5. The said retaining strip 15 is held or retained in position by means of a metal band 17 which encircles the holder in adjoining relation to the inner side of the notch 5, 15 as is clearly shown in the drawing. The outer end portion of the retaining strip 15 is inclined outwardly, as indicated at 18, to facilitate the movement of the said outer end portion into position over a cigarette, as shown 20 in Figs. 1 and 2. In order to facilitate the withdrawal of the retaining strip into retracted position as shown in Fig. 4 of the drawing, I have provided the inner end thereof with an outwardly extending projection 25 20. The said projection when the strip is moved forwardly, as shown in Figs. 1 and 2, contacts with the inner edge of the encircling metal band 17. The movement of the strip in the opposite direction is limited by 30 the contact of the inner end thereof with a shoulder 21 at the inner end of the shallow groove 16.

In Figs. 5 and 6 I have shown a construction embodying the invention in which the 40 opening 2 terminates inwardly of the outer end of the holder 1 and in which also the outer end of said opening is in communication with a cylindrical hole or passageway 25, which extends through the said holder. In 45 the form of construction as illustrated in these two figures no means is provided for automatically puncturing the wrappers of cigarettes as they are inserted endwise through the opening 25. Said wrappers 50 should be punctured prior to their insertion through said opening. The opening 25 is cylindrical in cross section as shown, and of a size such that the cigarettes fit more or less closely therein.

55 In Figs. 7 and 8 of the drawings I have shown a holder of the form illustrated in Figs. 1 to 4 having means whereby, when a holder is placed upon a table or other support, the forward or outer cigarette-holding 60 portion thereof may be sustained in elevated relation to the top of such table or other support. The means provided or employed for that purpose comprises a metal wire bent to the shape shown in Fig. 8 having opposite side portions 27, the inner ends of which

terminate in laterally and inwardly projecting portions 28 and 28'. The portions 28 are adapted to enter holes 29 provided upon opposite sides of the holder in diametrical relation to each other. The lower end portion of the holder-supporting device is bent laterally and slightly widened, as indicated at 30. When in use for supporting the outer cigarette-holding end portion of the holder in elevated position, as shown in Fig. 7, 70 the supporting or sustaining device occupies the full line position shown in Fig. 7, but when not in use for sustaining the holder the said device is folded back into the dotted line position shown in Fig. 7 and is retained in such position because the distance between the points *a* and *b* upon the wire-supporting or sustaining device is less than the diameter of the holder at the point where the swinging end portion of the said sustaining device engages the said holder. When the wire-supporting or sustaining device is in the position as illustrated in dotted lines in Fig. 7 the points *a* and *b* thereof are located beyond a horizontal central plane through the cigarette holder, and in consequence thereof the said sustaining device is retained in position shown in dotted lines until it may be desired to use the same in the manner as shown in Fig. 7. 80

85 It will be seen that by my invention I have provided a simple means whereby cigarettes may be supported at their middle portions and ignited at both ends, whereby smoke may be drawn by the smoker from both ends 90 simultaneously.

95 It will be noted also that the holder, especially when a cigarette is mounted thereon, presents somewhat the appearance or design of an aeroplane being thereby rendered especially attractive.

105 Although in the specification I have referred to the holder as being adapted for holding cigarettes while the latter are smoked, it will be understood that the holder is likewise adapted for holding small cigars or cigars of a size to permit the mounting thereof either in the notch 5, shown in the holder illustrated in Figs. 1 to 4 and 7, or in the passageway 25 shown in the holder illustrated in Figs. 5 and 6.

110 Having thus described my invention, what I claim and desire to secure by Letters Patent is:

115 1. A holder for holding cigarettes at points intermediate their opposite ends when they are being smoked, the said holder comprising an elongated stem-like portion having a passageway extending lengthwise thereof through which the smoke from a burning cigarette is adapted to be drawn and the said holder having at its outer end an opening extending transversely therethrough with which the outer end of the said lengthwise extending passageway is in communication, 120

the said transversely extending opening being adapted to receive and hold a cigarette.

2. A holder for holding cigarettes while being smoked, the said holder comprising an elongated stem-like member having a passageway extending therethrough through which smoke from a cigarette is adapted to be drawn and the said holder having in adjoining relation to its outer end a notch extending transversely thereof, with which notch the outer end of the said lengthwise extending passageway is in communication, the said notch being adapted to receive and hold a cigarette at a point intermediate its opposite ends whereby either end or both ends of said cigarette may be lighted, and the said holder being provided with means for automatically puncturing the wrappers of said cigarettes as they are inserted into the said notch.

3. A holder for holding cigarettes while they are being smoked, the said holder comprising an elongated stem-like portion having a passageway extending lengthwise thereof through which the smoke is adapted to be drawn from a burning cigarette and the said holder having a notch extending transversely therethrough adjoining its outer end with which notch the said lengthwise extending passageway is in communication, and the said notch being adapted to receive an intermediate portion of a cigarette and to hold the latter in transverse relation to the said holder, and the said holder being provided with a device for puncturing the wrapper of a cigarette as it is inserted into the said notch, and means adapted to be adjusted into position to retain a cigarette in place within said notch.

4. A holder for holding cigarettes while they are being smoked, the said holder comprising an elongated stem-like portion having a passageway extending lengthwise thereof through which smoke is adapted to be drawn when a cigarette is being smoked, the said holder also being provided with a notch adjoining its outer end and extending transversely thereof, with which notch the said lengthwise extending passage is in communication, a pointed metal device projecting into one side of said notch and adapted to puncture a wrapper of a cigarette when it is inserted transversely of its length into the said notch, a device slidably mounted upon the said holder and adapted to be moved into position over the said notch to retain a cigarette in place therein, and means mounted upon said holder for securing said retaining device upon the said holder.

5. A holder for holding cigarettes at points intermediate their ends while smoking the same, the said holder being of elongated stem-like form and having a passage extending lengthwise therethrough and also having an opening extending transversely thereof

within which a cigarette is adapted to be inserted and to be held while being smoked, the said passage terminating at one end in said opening and means mounted on said holder and projecting into said opening for puncturing the wrappers of cigarettes as the latter are placed in said opening.

In testimony that I claim the foregoing as my invention, I have hereunto signed my name this 9th day of December, A. D. 1927.

JAMES HERMAN ABBOTT.
